UNITED STATES PATENT OFFICE

ARTHUR A. GROTHE, OF OAK PARK, ILLINOIS, ASSIGNOR TO WILLIAM J. CAMERON, OF CHICAGO, ILLINOIS

OSCILLATORY MOTOR FOR ELECTRICALLY OPERATED SAFETY RAZORS

Application filed November 18, 1929. Serial No. 407,834.

Generically, my present invention pertains to apparatus that are vibrated through the medium of an electric current and it has more particular reference to a safety razor that is caused to operate by the vibration of the apparatus. The construction of the apparatus is such that I may assemble the parts so that the post for the razor carrying head and the actuating mechanism for causing the vibration are mounted upon a plug in the form of a unitary structure in order that they may be readily inserted in or removed from a tubular handle or grip. Another feature of the present structure is that the post for the razor-head, (which is outside the handle) and the vibratory actuating mechanism (which is housed in the handle) are carried by a common plug but are independent of each other. The assembly of the parts is such that water or moisture is prevented from entering the handle or causing damage to the operating mechanism or short-circuiting the electrical elements.

And further, the terminal connector at the end of the conductor cord is frictionally and non-rotatively maintained in assembly with the end of the handle so that the interior structure cannot become disturbed by an attempt to rotate the connector. This is essential and the disclosed structure is designed to take strain off the terminal pins at the end of the handle.

My invention has numerous objects in view among which may be mentioned the provision of a vibratory safety razor that is compact in construction; is novel in the arrangement of its parts; is dependable in operation, and is durable in construction. Further objects will be apparent after an understanding of my invention is had. I prefer to accomplish said objects, and to carry out my invention, in substantially the manner hereinafter fully described and as more particularly pointed out in the claims, reference being now made to the accompanying drawings that form a part of this specification.

In the drawings:—

Figure 1 is a vertical longitudinal view of the actuating structure of my improved safety razor.

Figure 2 is an elevation of the structure shown in Figure 1 looking at the right side thereof and showing the handle or grip in section.

Figures 3 and 4 are views, on an enlarged scale, showing in detail the arrangement of a spring contact member in two positions of operation.

Figure 5 is a detail view of the lower end of the handle showing the locking arrangement. 60

Figure 6 is an end view of the connector or plug that cooperates with the handle end structure.

Figure 7 is a longitudinal side view of the part shown in Figure 6.

Figure 8 is a perspective of the retainer ring or friction band.

The drawings it will be understood are somewhat schematic for the purpose of illustrating a typical or preferred form in which my invention may be made, and in said drawings I have employed similar reference characters to designate like parts wherever they appear throughout the views. 75

The structure shown consists of an electromagnet core 10 forming the body of a spool that has upper and lower retaining flanges 11 and 12 between which there is an energizing winding 13 that has electrical 80 connection at one end with core 10 in the usual manner. At the upper or outer end of the core there is a head or pole 14 that is suitably secured to the core in any manner. A substantially L-shaped bracket 15 is secured 85 to the lower end of the core and has its vertical arm disposed along one side of the coil in the manner shown in order to support an armature bar 16 that is connected to the vertical arm by the flat spring 17. The spring 90 and bar are of magnetic material and engage a pole piece 9 at the lower end of the coil and when the current is passing through said coil the armature bar will be attracted towards the upper pole piece 14. 95

A substantially U-shape yoke 18 is disposed with its parallel arms horizontal, and has one of said arms secured to the pole piece 14. This yoke is made of non-magnetic material, and the portion that connects the arms 100

affords an abutment against which a hammer 19 on the end of the armature will strike when the armature is vibrated. In order to cushion the impact of the hammer against the abutment a buffer or cushion 20 is preferably imbedded in the hammer so that a portion protrudes to strike the impact yoke between the arms of the latter. As will be seen the arms of the abutment yoke provide a space which accommodates the hammer 19 and thereby reduces the transverse dimensions of the structure.

The vertical arm of bracket 15 carries a spring contact member 21 that is mounted so as to extend up upon the upright arm alongside the armature bar 16, and it is insulated from the arm by pieces of insulating material 22.

The spring member terminates at about midway the length of the coil where it carries a contact block 23. A readily yielding spring member 24 is mounted or anchored at its upper end on the armature bar 16 and extends down to the upper end of member 21 where it is provided with a contact block 25, while intermediate its ends this spring member is engaged with a headed pin 26 that acts both as a guide to prevent sidewise movement and as a stop to maintain the spring in the desired relation to the coacting parts of the structure.

As seen in somewhat exaggerated detail in Figs. 3 and 4 the spring 24 in normal or rest position is slightly bowed outwardly and is not engaged with the pin head, and the contact blocks have their engaging surfaces flat against each other; but when the armature bar 16 that carries the spring moves towards the coil the spring 24 begins to straighten until the head of the pin is engaged and thereafter the contact block 25 begins to separate at its upper edge from the opposing block 23 until only the lower corners are engaged. The final break between the blocks occurs at about the time the armature bar 16 reaches the limit of its movement towards the coil, and as this break is at the lower corners of the blocks 25 and 23 the liability of pitting the smooth surfaces of said blocks is practically eliminated, and the blocks are separated by a quick break-away. The blocks are engaged while the armature bar is in a retracted position, and, on account of the above described arrangement, when the armature is attracted the blocks electrically disengage by a delayed or retarded breakaway thus opening the electromagnetic energizing circuit.

The coil and the bracket are secured to a base 27 of insulating material, the horizontal arm of the bracket being inlaid in the adjacent surface of the base, and a pair of terminals 28 and 29, of irregular shape, pass through the base, the terminal 28 being connected by a wire or conductor 30 to the energizing

winding 13 and the terminal 29 being connected by a conductor or wire 31 to the lower end of the contact arm 21. The other end of the winding has the usual connection with the electromagnet core. The terminals 28 and 29 pass out of the lower end of the base 27 parallel to each other so as to be engaged with socket contact elements 45 at the end of an electric cord 39 leading from a suitable source of current shown in Figures 6 and 7.

The structure hereinbefore described, as will be seen from Fig. 1, is of a unitary character and is therefore capable of ready removal from or insertion in the hollow or tubular handle or grip. In order to mount the unit within the handle I provide a threaded plug 32 to which the upper horizontal arm of the abutment yoke 18 is suitably connected. A tool-post 33, of a design capable of removably receiving a tool-head or blade-holder is imbedded in the upper or outer portion of the plug 32. The plug 32 is screw-threaded on its exterior and is adapted to be inserted and screwed part way into the threaded upper portion of a tubular grip or handle 34 that is fabricated from bakelite or other insulating material. After the plug has been screwed the desired distance into the handle, a cone-shaped cap 35 is screwed upon the protruding portion of the plug in the manner shown in Figure 2.

At the lower end of the handle there is a shouldered portion 36, that is formed by reducing the bore of the handle or by inserting a threaded bored plug, and a central aperture 37 is thus provided to accommodate the terminals 28-29 and to receive the socket structure or terminal connector 38 at the end of a lead-cord 39 containing the current conductors. When the parts are being assembled in the handle or grip the plug 32 carrying the unit is screwed into the end of the handle until the base 27 abuts the lower shoulder 36, thus maintaining the unit in the handle between the plug 32 and shoulder 36. This construction and assembly permits the ready removal of the unit from the handle for the purpose of inspection, replacement, or repair.

A portion of the reduced bore of the central lower aperture 37 has longitudinal grooves 40 to receive one or more (preferably two) spurs 41 projecting radially from the outer edge of a lock-ring 42 whereby the latter is maintained against accidental or intentional rotational movement. When two spurs are used they are not placed diametrically opposite or aligned with each other but one is offset with respect to the other the space of a groove 40, so that, by overturning the lock-ring or by placing the spurs in other grooves, the relation of the hereinafter described parts may be modified as desired. The inner periphery of the lock-ring has one or

more (preferably two) diametrically alining inwardly projecting lugs 43, and the exterior of the connector 38 has counterpart channels 44, extending longitudinally thereon. As the 5 inner diameter of lock-ring 42 is sufficient to accommodate the connector, the latter may be inserted only when its channels 44 are registered with lugs 43, and that after insertion any attempt to rotate the connector is 10 prevented by the spurs 41 engaged with the grooves 40.

After the operating unit has been inserted into the handle, the lock-ring is placed in 15 position so that the plane of lugs 43 will intersect the plane in which the terminals 28 and 29 are disposed. The connector 38 is provided with a pair of tubular or socket terminals 45 arranged in a plane intersected by the plane of the channels 44 and have the 20 conductor wires connected to their inner ends. The construction and disposition of the connector element and the coacting parts at the end of the handle are such that the lock ring may be "set" according to the position 25 assumed by the terminals when the unit is inserted into the handle, and thereafter when the connector has been inserted the latter cannot rotate nor can it cause a rotation of the operating unit within the grip. 30 The exterior of the lower end of the grip is threaded and a cup-shaped cap 46, having a central opening, is screwed thereon, for the purpose of increasing friction with the connector I have interposed a split spring 35 band or ring 47 between the inner face of the cap and the adjacent end of the handle. Said friction band is preferably of slightly less internal diameter than the outside diameter 40 of the connector, so that the latter must be pushed through the band when being inserted.

What I claim is:—

1. A device of the character disclosed 45 comprising an electromagnet core having an energizing winding, an armature vibrated by said electromagnet, an abutment impacted by said armature, a pair of terminals one of which is connected to said winding; an arm alongside said electromagnet and electrically 50 connected to the other terminal, a contact block on said arm, a yielding arm carried by said armature, and a contact block on said yielding arm, the arrangement of said arms and blocks being such that the movement of 55 the armature towards the electromagnet permits a delayed break between the blocks and a tilting of one of the blocks at the moment of break.

2. In a vibrator device a hollow handle having an apertured lower end, an electro-responsive unit within the handle having terminals extended into the aperture, a lock-ring anchored in said aperture and having an inwardly extending projection, and a connector 65 removably inserted in said aperture and hav-

ing a longitudinal channel coacting with said projection to prevent axial rotation of said connector.

3. In a vibrator device a hollow handle having an apertured lower end, an electro-responsive unit within the handle having terminals 70 extended into the aperture, a lock-ring anchored in said aperture and having an inwardly extending projection, a connector removably inserted in said aperture and having a longitudinal channel coacting with said 75 projection to prevent axial rotation of said connector, and a friction band adjacent said lock-ring through which said connector is inserted.

4. A device of the character disclosed comprising an electromagnet core, an energizing winding thereon, an abutment associated with one end of said electromagnet, a bracket at the opposite end of said electromagnet, a vibratory armature yieldably mounted on 80 said bracket and actuated by said electromagnet to impact said abutment, a yieldable contact arm mounted on said bracket alongside 85 said electromagnet, a yieldable bowed contact arm carried by said armature and having limited movement independent of the armature, the second arm extending towards and coacting with the other contact arm, and a pair of terminals electrically connected respectively to the first named contact arm and 90 said winding.

5. A device of the character disclosed comprising an electromagnet core, an energizing winding thereon, an abutment associated with 100 one end of said electromagnet, a bracket at the opposite end of said electromagnet, a vibratory armature yieldably mounted on said bracket and actuated by said electromagnet to impact said abutment, a yieldable contact arm extending alongside said electromagnet, a yieldable bowed contact arm carried by said armature and having limited movement independent of the armature, the second arm extending towards and coacting 105 with the other contact arm, a pair of terminals electrically connected respectively to the first named contact arm and said winding, and members at opposite ends of said structure 110 to which the adjacent portions thereof are 115 connected.

6. A device of the character disclosed comprising a hollow handle, an electromagnet therein, a removable end plug connected to said electromagnet, an abutment within said 120 handle, a bracket remote to said abutment, an armature yieldably mounted on said bracket and vibrated by said electromagnet to impact said abutment, a yieldable contact arm alongside said electromagnet, a yielding 125 bowed contact arm carried by said armature, and having limited movement independent of the armature, the second arm extending towards and coacting with said first-named contact arm, a base attached to the lower por- 130

tion of the structure, and terminals carried by the base and connected to said winding and said first named contact arm.

7. A device of the character disclosed comprising a hollow handle, an electromagnet therein, a removable end plug connected to said electromagnet, an abutment within said handle, a bracket remote to said abutment, an armature yieldably mounted on said bracket and vibrated by said electromagnet to impact said abutment, a yieldable contact arm alongside said electromagnet, a yielding bowed contact arm carried by said armature, and having limited movement independent of the armature, the second arm extending towards and coacting with said first-named contact arm, a base attached to the lower portion of the structure, terminals carried by the base and connected to said winding and said first named contact arm, and a shoulder at the lower end of said handle against which said base is engaged when the structure is inserted within the handle.

8. In a vibratory device a hollow handle having an apertured lower end, an electro-responsive unit within the handle having terminals extended into the aperture, a lock ring anchored in said aperture, a connector removably inserted in said aperture, and tongue and groove elements on said two last named parts adapted to prevent relative rotational movement between the respective parts.

Signed at Chicago, Cook County, Illinois,
the 29th day of October, 1929.
